UNITED STATES PATENT OFFICE.

HENRY CRUSE, OF HYDE, AND TOM FREDERICK GRAY, OF MANCHESTER, ENGLAND.

STEAM SUPERHEATER.

Application filed July 23, 1927, Serial No. 208,027, and in Great Britain August 4, 1926.

This invention relates to steam superheaters and more particularly to superheaters for use with fire tube type boilers, such as locomotive boilers, in which the superheating tubes project into the ends of the fire tubes.

The object of our present invention is to provide an improved construction and arrangement of the superheater having a very efficient heating surface and improved means for the supply of the steam to and its distribution from the superheater.

Our invention comprises a superheater tube or element built up from two tubes placed one within the other, the two tubes being secured together by welding or otherwise at both ends and the inner tube being shaped, except at one end, where it is cylindrical, to an elliptical or like form, dividing the space within the outer tube into three portions, the inner elliptical space serving for the passage of the hot gases, and the two spaces on the opposite sides of the inner tube serving for the flow and return of the steam being superheated, the annular space around the cylindrical end of the inner tube serving for the transfer of the steam from the said flow to the said return space.

Referring to the two accompanying sheets of explanatory drawings:—

Figure 1 is an end elevation (with parts in section) and Figure 2 a sectional side elevation showing a part of the smoke box end of a locomotive boiler having our invention applied thereto.

Figure 3 is a similar view to Figure 1 showing a modified arrangement of the superheater elements.

Figure 4 is a plan showing the return end of one of the superheater elements.

Figures 5 and 6 are sections to a larger scale than that of the aforesaid figures, of two alternative forms of the superheater elements.

The same reference letters in the different views indicate the same or similar parts.

In one convenient application of our invention, and as illustrated at Figures 1 and 2, each superheater element which is inserted within a fire tube *a* of the boiler, comprises two cylindrical tubes *b* and *c* disposed within one another and such as to provide a space between them. At one end (the return end) the inner tube *c* is retained of cylindrical shape and is secured to the outer tube *b* by

welding or otherwise, leaving an annular space between the tubes. The said circular portion of the tube *c* is shown at *c*¹, Figure 4. The remainder of the inner tube *c* is formed to an elliptical or like section with the outside dimensions at its major axis equal to or slightly greater than the normal bore or internal diameter of the outer tube so that the space between the inner and outer tubes is divided into two parts serving for the flow and the return of the steam being superheated, as is shown by the sectional parts in Figure 1. The inner tube at its end where the steam enters and leaves the superheater element is of oval or like shape and is secured to the outer tube.

The inner oval or like tube *c* may be formed so that its major axis externally may be slightly greater than the internal diameter of the external tube *b*, the latter being heated to cause it to expand, and permit it to be shrunk on to, or otherwise forced on to or over the internal oval or like tube *c*, after which, by the cooling of the outer tube *b* shrinkage will take place, giving permanent contact or connection, and resulting in the outer tube being formed slightly elliptical. The pressure of the steam between the two tubes acting externally upon the oval or elliptical internal tube *c* will tend to expand the latter at its major axis, and acting internally upon the external tube will tend to contract the latter at its major axis.

It will be seen that the whole of the space between the inner and outer tubes is divided into two parts except at the end *c*¹ (Figure 4) where the inner tube *c* is cylindrical and where the steam being superheated is transferred from the flow to the return space of the superheater element. The space within the inner tube serves for the passage of the hot gases, as likewise does the space between the outer tube *b* and the smoke or fire tube *a*.

Two alternative forms of the tubes *b* and *c* of the superheater elements are shown at Figures 5 and 6. In both forms the spaces for the hot gaseous products of combustion are indicated by *d* and the steam spaces by *e*.

The outer tube *b* may have branches as *f* thereon to which steam inlet and outlet pipes may be secured. Or the branches of the outer tubes disposed vertically above and below (as with the example shown at Figures 1 and 2) or horizontally side by side of one another (as with the example shown

at Figure 3) may be secured directly to one another to provide for several passages of the steam through the superheating elements. Steam may be passed to the superheater elements from pipes as *g* leading from above to the vertical interconnected rows of elements (as in Figures 1 and 2) or to the horizontal interconnected rows of elements (as in Figure 3). The superheated steam delivery may be from a common horizontal pipe below the superheater, or midway, or at the sides of its horizontal length from one or more vertical pipes.

By passing the hot gases both on the inside and the outside of the steam being superheated, we obtain a large heating surface, one portion of which is clear of the cooling effect of the adjacent water heating surface.

20. What we claim is:—

1. In steam superheaters, a superheating element consisting in part of two tubes nested the one within the other, the outer tube being cylindrical throughout and the inner tube elliptical for the greater part of its length, but having a cylindrical portion at one end forming an annular space between the tubes, the major axis of the elliptical portion being substantially equal to the internal diameter of the outer tube.

2. In steam superheaters, a superheating element consisting in part of two tubes nested the one within the other, and permanently secured together at each end, the outer tube being cylindrical throughout and the inner tube elliptical for the greater part

of its length but having a cylindrical portion at one end forming an annular space between the tubes, the major axis of the elliptical portion being substantially equal to the internal diameter of the outer tube.

3. In steam superheaters, the superheating element consisting in part of two tubes nested the one within the other, and permanently secured together at each end, the outer tube being cylindrical throughout and the inner tube elliptical for the greater part of its length but having a cylindrical portion at one end forming an annular space between the tubes, the major axis of the elliptical portion being substantially equal to the internal diameter of the outer tube, and the two tubes permanently connected along such major axis.

4. In steam superheaters, a superheating element consisting in part of two tubes nested the one within the other, the outer tube being cylindrical throughout and the inner tube elliptical for the greater part of its length, but having a cylindrical portion at one end forming an annular space between the tubes, the major axis of the elliptical portion being substantially equal to the internal diameter of the outer tube, steam inlet and outlet branches on the outer tube and a boiler fire tube in which said element is inserted.

In testimony whereof we have signed our names to this specification.

HENRY CRUSE.
TOM FREDERICK GRAY.
